Whole No. 1469 - Charles A. Shaw & James B. Clark, of Biddeford, Maine.
Letters Patent No. 104, dated Aug. 13, 1861.

The schedule referred to in these Letters Patent and making part of the same.

To all to whom these presents shall come, Greeting:

Dec. 14 69

Be it known, that we, Charles A. Shaw and James B. Clark, of Biddeford,
in the County of York, and State of Maine, have invented or produced a new and original
design for a Sewing Machine, and we do hereby declare that the following is a full, and
exact description of the same, reference being made to the accompanying drawings forming
part of the same, in which drawings,

A represents the stand or body part of the machine, having a fluted
or ornamental edge $\textcircled{c}$, and otherwise constructed as shown, $\textcircled{a} \textcircled{a} \textcircled{a} \textcircled{a}$ is a four posted
or four legged upright or standard having the two arms $\textcircled{2} \textcircled{2}$, which unite in the head $\textcircled{v}$.

The standard $\textcircled{a} \textcircled{a} \textcircled{a} \textcircled{a}$ has a four sided pyramidal shaped top $\textcircled{a} \textcircled{a}$,
with slightly convex sides, which converge to the base of the parts $\textcircled{t} \textcircled{t}$. Around the
standard or upright, at the base of the pyramidal shaped top $\textcircled{a} \textcircled{a}$, is an ornamental
moulding as shown at $\textcircled{b} \textcircled{b}$. The principal feature of our design is the gothic, open,
or four posted standard $\textcircled{a} \textcircled{a} \textcircled{a} \textcircled{a}$, taken as a whole, which with its arms $\textcircled{2} \textcircled{2}$, and
head $\textcircled{v}$, is cast or constructed in one piece, and which when properly constructed and
finished, gives our machine a peculiarly light and elegant appearance.

We claim the ornamental design for the standards $\textcircled{a} \textcircled{a} \textcircled{a} \textcircled{a}$ as
shown in the drawings and herein described.

Witnesses.
